UNITED STATES PATENT OFFICE

107,501

DESIGN FOR A TOILET ODOR EXPELLER CASING

Gaspé H. Davis, Van Nuys, Calif.

Application September 15, 1937, Serial No. 71,639

Term of patent 3½ years

To all whom it may concern:

Be it known that I, Gaspé H. Davis, a citizen of Canada and resident of Van Nuys, Los Angeles County, State of California, have invented a new, original, and ornamental Design for a Toilet Odor Expeller Casing, of which the following is a specification, reference being had to the accompanying drawing, forming a part thereof:

I claim:

The ornamental design for a toilet odor expeller casing substantially as shown.

GASPÉ H. DAVIS.
